UNITED STATES PATENT OFFICE.

LOUIS PATUREL AND PIERRE LAPERTOT, OF ST.-ÉTIENNE, FRANCE.

INTERNAL-COMBUSTION GAS-TURBINE.

1,133,058.

Specification of Letters Patent. Patented Mar. 23, 1915.

Application filed October 31, 1913. Serial No. 798,521.

To all whom it may concern:

Be it known that we, LOUIS PATUREL and PIERRE LAPERTOT, citizens of the French Republic, residing at St.-Étienne, in France, 5 have invented certain new and useful Improvements in Internal-Combustion Gas-Turbines, of which the following is a specification.

This invention has for its object a gas 10 turbine in which the combustion of the combustible mixture is produced in a chamber in which the pressure and the temperature are such that the self-ignition of the compressed explosive mixture takes place 15 when it enters in the chamber, as in certain internal combustion motors.

In order that the invention may be well understood it is illustrated by way of example in the annexed drawing.

20 Figure 1 is a vertical longitudinal section of the turbine. Fig. 2 is a transverse section of the upper half part of the same on line 2—2 of Fig. 1.

The turbine comprises a casing A¹ in 25 which is a chamber A, having a number of distributors B and surrounded by the vanes C of a rotor D keyed on a shaft E.

The motive power is furnished by the action on the vanes C of combustion gases, 30 said combustion in the chamber A being continuous. With this object in view the air and gas or spirit are separately introduced into said chamber A by means of an injector F, and owing to the pressure and 35 temperature in said chamber due to the ignition of the mixture previously ignited the fresh mixture is ignited as soon as it is introduced, giving rise to a super-pressure which counterbalances the loss of charge 40 due to the continual discharge through the distributors B. This cycle of working is indefinitely continued if the quantities of air and gas or spirit are exactly proportioned to the discharge by the distributors. 45 The motive gases act on the vanes C as in an ordinary turbine. After the expansion of the gases they are collected in a crown G having a discharge collector H.

In order to obtain a good calorific insulation of the chamber A, it is surrounded by a jacket of asbestos I also forming an insulating sleeve around the shaft E. The counter-pressure due to the expanded gases is reduced to the minimum by a circulation 55 of fresh air produced by wings J fixed to

the wheel D. The air is sucked in from the outside by the rotation of the wings through the space J¹ and is driven into the collector G and expels the burned gases therefrom. This fresh air also cools the vanes and crown 60 of the turbine.

According to the arrangement illustrated the motive power is transmitted from the shaft E to a speed reducer K which commands the air compressor, the pump and 65 other accessories of the turbine.

What we claim as our invention and desire to secure by Letters Patent of the United States is:—

1. An internal combustion gas turbine 70 comprising a casing, an annular combustion chamber therein in which high temperature and pressure are maintained by the continuous ignition of a combustible mixture, a rotor, vanes thereon, means for injecting 75 air and fuel separately into said chamber, means for directing the burned gases from said chamber onto the vanes of said rotor, a shaft supporting said rotor, a heat insulating jacket surrounding said annular 80 chamber and also forming an insulating sleeve around said shaft, a collecting chamber surrounding said rotor, and means for cooling said rotor and for discharging the burned gases out of the collecting chamber. 85

2. An internal combustion gas turbine comprising a casing, an annular combustion chamber therein in which high temperature and pressure are maintained by the continuous ignition of a combustible mixture, a 90 rotor, vanes thereon, means for injecting air and fuel separately into said chamber, means for directing the burned gases from said chamber onto the vanes of said rotor, a shaft supporting said rotor, a heat insulating jacket surrounding said annular 95 chamber and also forming an insulating sleeve around said shaft, a collecting chamber surrounding said rotor, and wings on said rotor adapted to suck fresh air into 100 said collecting chamber to expel the burned gases therefrom and also to cool said rotor.

In witness whereof we have signed this specification in the presence of two witnesses.
